UNITED STATES PATENT OFFICE

PAUL TRIPKE, OF JERSEY CITY, NEW JERSEY

DESIGN FOR A CASING FOR A COMBINED COFFEE GRINDER, JUICE EXTRACTOR, FOOD CUTTER, AND MIXER

Application filed March 20, 1931. Serial No. 39,171. Term of patent 14 years.

To all whom it may concern:

Be it known that I, PAUL TRIPKE, a citizen of the United States and resident of Jersey City, in the county of Hudson and State of New Jersey, have invented a new, original, and ornamental Design for a Casing for a Combined Coffee Grinder, Juice Extractor, Food Cutter and Mixer, of which the following is a specification, reference being had to the accompanying drawings, forming part thereof.

Referring to the drawings:

Figure 1 is a perspective view of the article, showing my new design.

Figure 2 is an end view taken at —A— (at

Fig. 1) and looking in the direction of arrow.

Figure 3 is an end view taken at —B— (at Fig. 1) and looking in the direction of arrow.

Figure 4 is another perspective view, viewing it from the front.

Figure 5 is a top view.

I claim:

The ornamental design for a casing for a combined coffee grinder, juice extractor, food cutter, and mixer, as shown.

Signed at Jersey City, in the county of Hudson and State of New Jersey, this seventeenth day of March, A. D. 1931.

PAUL TRIPKE.
